DESIGN FOR A TELEPHONE DESK STAND

Application filed May 23, 1930. Serial No. 35,739. Term of patent 7 years.

To all whom it may concern:

Be it known that we, GEORGE R. EATON and ROYAL HORN, citizens of the United States of America, residing at Oak Park and Chicago, respectively, in the county of Cook and State of Illinois, have invented a new, original, and ornamental Design for Telephone Desk Stand (Case No. 873), of which the following is a specification, reference being had to the accompanying drawing, forming part thereof.

Fig. 1 is a perspective view of the telephone desk stand showing our new design;

Fig. 2 is a top plan view; and

Fig. 3 is a side elevation thereof.

We claim:

The ornamental design for a telephone desk stand, substantially as shown.

GEORGE R. EATON.
ROYAL HORN.
